CLAIM

The ornamental design for an article holder with coin sorter, as shown and described.

DESCRIPTION

FIG. 1 is a perspective view of an article holder with coin sorter showing our new design;
 FIG. 2 is a top plan view thereof;
 FIG. 3 is a front elevational view thereof;
 FIG. 4 is a rear elevational view thereof;
 FIG. 5 is a bottom plan view thereof; and,
 FIG. 6 is a left side elevational view thereof, with the right side elevational view being a mirror image thereof.
